UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed October 10, 1930. Serial No. 487,656.

This invention relates to car roofs of the type wherein the metal roof sheets are rigidly secured together and to the carlines along their adjacent margins. It has for its principal objects to produce a strong and light weight roof of simple and economical construction that is easy of application and that will enable portions of the sheets to flex or bend relative to each other and to the carlines and thereby prevent damage to the sheets when the car frame is distorted in service. Other objects are to reduce the height of the carline without sacrificing strength or headroom, to better provide for supporting the sheets on the carlines, and to facilitate the operation of riveting the sheets to the carlines. The invention consists principally in spacing portions of the sheets from the carlines to which they are secured so that said sheets may flex relative to the carlines and to each other; it also consists in providing the carlines with portions that serve as supports for the roof sheets; it also consists in the arrangements and combinations of parts hereinafter described and claimed.

In the accompanying drawings, which form part of this specification and wherein like symbols refer to like parts wherever they occur,

Fig. 1 is a plan view of a portion of a car roof embodying my invention,

Fig. 2 is an enlarged vertical transverse cross-section through the roof on the line 2—2 in Fig. 1,

Fig. 3 is a vertical section on the line 3—3 in Fig. 2,

Fig. 4 is a vertical cross-section on the line 4—4 of Fig. 2; and

Figs. 5 and 6 are vertical sections similar to Fig. 3, showing modified seam constructions.

The present construction comprises Z-bar side plates A connected by carlines B, and roof sheets C extending from side plate to side plate and covering the spaces between carlines. The Z-bar side plates A are preferably arranged with the inner flange 1 upstanding and having an angle-shaped support D riveted flatwise to the outer face of said flange. The upper flange 2 of the angle-

shaped support D extends inwardly over the side plate beneath the roof sheets C at an angle corresponding to the slope thereof at the proper elevation for the end portions of said roof sheets to rest upon. At suitable intervals the upper flange 2 of the angle-shaped support D is provided in its top with depressions 3 shaped to receive and form seats for the ends of the carlines B, which are riveted thereto.

The carlines B are made up of two members each, an upper member 4 and a lower member 5. The upper member 4 comprises an inverted channel with outstanding base flanges 6 at the lower edges of its side walls, the channel being of uniform depth from the ridge to points adjacent to the eaves where it is curved downwardly to close its ends. The lower carline member 5 is in the form of a plate that is riveted to the base flanges of the inverted channel-shaped upper carline member 4. The lower carline member 5 is wider than the upper carline member 4 and has its side marginal portions offset upwardly beyond the base flanges of said upper carline member to form raised flanges or panels 7 for the roof sheets C to rest upon.

The roof sheets C extend from side plate to side plate and are provided at their ends with depending flanges 8 that overhang and that are preferably spaced from the combined carline and roof sheet supports D and the upstanding side plate flanges 1, to which said supports are secured. The roof sheets are provided along opposite side margins with inverted channel-shaped side marginal flanges or hollow ribs 9 that extend from end to end of the roof sheets. The channel-shaped side marginal flanges 9 of adjacent roof sheets fit and interlock with each other and straddle the carlines. Said flanges are riveted flatwise, as at 10, to the tops of the carlines B and are so wide that the side walls of said ribs are spaced from the side walls of said carlines. This arrangement affords clearance between the sheet ribs and carlines on both sides of the latter and thus permits the portions of the sheets between carlines to shift or flex and in this manner

accommodate themselves to the distortions to which the car frame is subject in service.

Holes 11 are formed in the bottom member 5 of the carlines below the rivets 10 so as to facilitate riveting. Any water that gets under the roof sheets onto said lower carline members will drain lengthwise of said member and be discharged over the ends thereof outside of the car. Such water is prevented 10 from passing through the holes 11 by flanging up the edges thereof.

In the modified construction shown in Fig. 5, each of sheet C' is provided along one side margin with a simple upstanding flange

15 12 that lies flatwise against one side of the carline B, and along the opposite side margin with an inverted channel-shaped flange or hollow rib 13 that clears the near side of said carline but has its outermost flange or wall 20 bearing flatwise against the simple upstanding flange 12 of the adjacent sheet. The sheets are secured together and to the carline by a single row of rivets 14 that pass horizontally through the overlapping portions of 25 the sheet flanges and the adjacent side wall of the carline.

By the arrangement described, the roof sheets have their adjacent margins supported on and rigidly secured to the carlines, but, at 30 the same time, are capable of flexing or shifting independently thereof when the car frame distorts in service. The carline construction functions after the manner of a hollow box girder; it enables the height of the carline 35 to be reduced without sacrifice of strength or head room; and it provides a better support for the roof sheets and also facilitates the operation of riveting the roof sheets to the carlines.

40 The modified construction of Fig. 6 shows a one-piece outside carline, as distinguished from the two-piece inside carline constructions hereinbefore described. The outside carline B' of this construction comprises a 45 single member of inverted channel-shaped cross-section having outstanding base flanges which bear flatwise upon the body portions of adjacent roof sheets. The roof sheets are similar to those shown in Fig. 5; that is, each 50 sheet C'' is provided along one side margin with its simple upstanding flange 12a and along the opposite side margin with inverted channel-shaped flange or hollow rib 13a. In this construction, however, the cooperating 55 flanges of adjacent roof sheets are located inside the outside carline B' with the outer wall of the hollow rib 13a of one sheet lying flatwise against the inner face of one side wall of said carline and overlapping the simple 60 upstanding flange 12a of the adjacent sheet. The sheets are rigidly secured together and to the carline by a row of rivets 14a that pass horizontally through the overlapped portions 65 of said sheets and the adjacent side wall of said carline. The channel of the outside car-

line B' is made deep enough and wide enough to afford clearance between the said carline and the hollow rib 13a at the top and unsecured side wall of said rib. With this arrangement, the space between one side wall of the hollow rib 13a and the adjacent side wall of the carline permits the body of the sheet to flex or shift transversely of the carline in accommodating itself to the weaving of the car, while the space between the top of said rib and the top of the carline permits the top wall of said rib to tilt crosswise during such flexing or shifting of the sheet.

What I claim is:

1. A car roof comprising side plates, inverted channel-shaped carlines connecting said side plates, and roof sheets supported on said side plates and carlines, said roof sheets being provided along their adjacent margins with cooperating flanges that are shaped to form hollow ribs that cooperate with the channels of said carlines, said ribs being rigidly secured to said carlines, each carline and the rib cooperating therewith being of different width so as to provide a space between at least one side of a rib and the adjacent side of a carline.

2. A car roof comprising side plates, carlines connecting said side plates, and roof sheets supported on said side plates and carlines, said roof sheets being provided along their adjacent margins with cooperating flanges that are shaped to form hollow ribs that straddle said carlines, said ribs being rigidly secured to said carlines and being wide enough to provide clearance between at least one side of a rib and the adjacent side wall of the carline straddled thereby.

3. A car roof comprising side plates, carlines connecting said side plates and having side marginal extensions, roof sheets supported on said carline extensions and provided along their adjacent margins with cooperating flanges that are shaped to form hollow ribs that straddle said carlines, each of said ribs being rigidly secured along one side to one side of a carline and being spaced from the opposite side of said carline.

4. A car roof comprising side plates, carlines of hollow box section connecting said side plates and having its bottom member extended laterally beyond the sides and offset upwardly to form supports for roof sheets, and roof sheets supported on said side plates and carlines, said roof sheets being provided along their adjacent margins with hollow ribs which embrace each other, said ribs being rigidly secured together and to the top of each carline with their sides enclosing and spaced from the sides thereof.

5. A car roof comprising side plates, carlines of hollow box section connecting said side plates and having its bottom member extended laterally beyond the sides and offset upwardly to form supports for roof

sheets, and roof sheets supported on said side plates and carlines, said roof sheets being provided along their adjacent margins with hollow ribs which embrace each other, said 5 ribs being riveted together and to the top of each carline with their sides enclosing and spaced from the sides of the latter, said carlines having openings formed in their bottoms adjacent to the points where the roof 10 sheet ribs are secured to the carlines.

6. A car roof comprising side plates, carlines of inverted channel-shaped cross-section connecting said side plates, and roof sheets supported on said side plates and carlines, said roof sheets being provided along 15 their adjacent margins with inverted channel-shaped flanges that embrace each other and straddle said carlines, said flanges being rigidly secured flatwise to the tops of said 20 carlines and being spaced from the sides thereof.

7. A car roof comprising side plates, carlines connecting said side plates, and roof sheets supported on said side plates and carlines, each roof sheet being provided along 25 one side margin with a hollow rib and along its outer side margin with an upstanding flange, each of said sheets being arranged with its marginal rib astraddle a carline and 30 the marginal flange of an adjacent sheet, said flange and the wall of the rib adjacent thereto being rigidly secured together and to the adjacent side wall of said carline, said 35 rib being wider than said carline to provide clearance between said rib and the other side wall of said carline.

8. A car roof comprising side plates, carlines connecting said side plates, and roof sheets supported on said side plates and carlines, each roof sheet being provided along 40 one side margin with a hollow rib and along its outer side margin with an upstanding flange, each of said sheets being arranged with its marginal rib astraddle a carline and 45 the marginal flange of an adjacent sheet, said marginal flange and one side wall of said rib being rigidly secured together and to one side wall of said carline, the other side wall 50 of said rib being spaced from the other side wall of said carline.

9. A car roof comprising side plates, carlines connecting said side plates, and roof sheets supported on said side plates and carlines, each roof sheet being provided along 55 one side margin with a hollow upstanding rib and along its other side margin with an upstanding flange, each of said sheets being arranged with its upstanding marginal rib 60 astraddle a carline and with the outer wall of said rib lying against the upstanding marginal flange of an adjacent sheet, said flange and said outer wall of said rib being riveted together and to the adjacent side wall of said 65 carline, the inner wall of said rib being spaced from the other side wall of said carline.

10. A car roof comprising side plates, carlines connecting said side plates, and roof sheets supported on said side plates and carlines, each roof sheet being provided along 70 one side margin with a hollow upstanding rib and along its other side margin with an upstanding flange, each of said sheets being arranged with its upstanding marginal rib astraddle a carline and with the outer wall of said rib lying against the upstanding marginal flange of an adjacent sheet, said flange and said outer wall of said rib being riveted together and to the adjacent side wall of said 75 carline, the inner wall of said rib being spaced from the other side wall of said carline, said carline being of hollow box section with its bottom member extended beyond the sides and offset upwardly to support the roof sheets, said carline also having openings in its bottom located adjacent to the points where the sheets are riveted to the carline.

11. A car roof comprising side plates, carlines connecting said side plates, and roof sheets supported on said side plates and carlines, each roof sheet being provided along 80 one side margin with a hollow rib and along its outer side margin with an upstanding flange, each of said sheets being arranged with its marginal rib astraddle a carline and 85 the marginal flange of an adjacent sheet, said flange and the wall of the rib adjacent thereto being rigidly secured together and to the adjacent side wall of said carline, said rib being wider than said carline to provide 90 clearance between said rib and the other side wall of said carline, said carline being of hollow box section and having openings in its bottom located adjacent to the points where the sheets are secured to the carline, 95 said carlines having side marginal extensions constituting supports for said roof sheets.

12. A car roof comprising side plates, carlines connecting said side plates and roof sheets supported on said side plates and carlines, each roof sheet being provided along 100 one side margin with a hollow upstanding rib and along its opposite side margin with an upstanding flange, each of said sheets being arranged with its marginal rib fitting 105 within a carline and with the outer side wall of said rib lying against the upstanding flange of an adjacent sheet and riveted thereto and to the adjacent side wall of said carline, the inner side wall of said rib being spaced from the other side wall of said carline.

13. A car roof comprising side plates, carlines connecting said side plates and roof sheets supported on said side plates and carlines, each roof sheet being provided along 110 one side margin with a hollow upstanding rib and along its opposite side margin with an upstanding flange, each of said sheets being arranged with its marginal rib fitting 115 within a carline and with the outer side wall of said rib lying against the upstanding flange of an adjacent sheet and riveted thereto and to the adjacent side wall of said carline, the inner side wall of said rib being spaced from the other side wall of said carline.

within a carline and with the outer side wall of said rib overlapping the upstanding flange of an adjacent sheet and riveted thereto and to the adjacent side wall of said carline, the inner side wall of said rib being spaced from the other side wall of said carline, and the top of said rib being spaced from the top of said carline.

14. A car roof comprising side plates, inverted channel-shaped carlines connecting said side plates, and roof sheets supported on said side plates and carlines, said roof sheets being provided along their adjacent margins with cooperating flanges that are shaped to form hollow ribs that cooperate with the channels of said carlines, said ribs being rigidly secured to said carlines, each carline and the rib cooperating therewith being of different width and depth so as to provide a space between at least one side of a rib and the adjacent side of a carline, and a space between the top of said rib and the top of said carline.

Signed at New Kensington, Pennsylvania,
this 6th day of October, 1930.

CHARLES DAVID BONSALL.
